US0D1069687S

(12) **United States Design Patent** (10) **Patent No.:** **US D1,069,687 S**
(45) **Date of Patent:** **** Apr. 8, 2025**

(54) **OUTDOOR BATTERY PACK**

(71) Applicant: **CONTEMPORARY NEBULA TECHNOLOGY ENERGY CO., Ltd.**,
Fuzhou (CN)

(72) Inventors: **Zhengping Shi**, Fuzhou (CN);
Xiaoming Zheng, Fuzhou (CN)

(73) Assignee: **CONTEMPORARY NEBULA TECHNOLOGY ENERGY CO., Ltd.**,
Fuzhou (CN)

(**) Term: **15 Years**

(21) Appl. No.: **29/836,651**

(22) Filed: **Apr. 28, 2022**

(30) **Foreign Application Priority Data**

Oct. 29, 2021 (CN) 202130711068.1

(57) **CLAIM**

The ornamental design for an outdoor battery pack, as shown and described.

DESCRIPTION

FIG. 1 is a front perspective view of an outdoor battery pack showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in the drawings illustrate the portions of the outdoor battery pack which form no part of the claimed design.

1 Claim, 7 Drawing Sheets
